UNITED STATES PATENT OFFICE.

PORTER M. GRIFFITH, OF SAN FRANCISCO, CALIFORNIA, ASSIGNOR TO GRUEN-HAGEN'S, OF SAN FRANCISCO, CALIFORNIA, A CORPORATION OF CALIFORNIA.

DESIGN FOR A BOOK END.

Application filed October 7, 1925. Serial No. 15,052. Term of patent 3½ years.

To all whom it may concern:

Be it known that I, PORTER M. GRIFFITH, a citizen of the United States, residing at the city and county of San Francisco, State of California, have invented a new, original, and ornamental Design for Book Ends, of which the following is a specification, reference being had to the accompanying drawing, forming part thereof.

The Figure 1 is a front view of a book end showing my new design, and

The Figure 2 is a side elevation of the same.

I claim:

The ornamental design for a book end, as shown.

PORTER M. GRIFFITH.
